(57) **ABSTRACT**

Provided is a writing tool comprising a clip composed of a wire rod, wherein the writing tool is capable of allowing a user to raise the clip without manipulation with both hands. The writing tool 1 comprises a tool body 7 extending in a longitudinal direction, and a clip member 8 composed of a wire rod and held by a lateral portion of the tool body 7, wherein a longitudinal intermediate portion 8B of the clip member 8 is held by the lateral portion of the tool body 7, and the clip member 8 is biased toward the tool body 7 so as to cause a longitudinal fore-end portion 8A of the clip member 8 to come into contact with the tool body 7, and wherein the writing tool is configured such that, when a back-end portion 8C of the clip member 8 is pushed toward the tool body 7, the fore-end portion 8A of the clip member 8 is swung to be spaced apart from the tool body 7.

WRITING TOOL

TECHNICAL FIELD

The present invention relates to a writing tool, and more particularly to a writing tool comprising a tool body and a clip whose intermediate section is swingably supported by a lateral portion of the toll body.

BACKGROUND ART

Heretofore, in the field of writing tools such as a ballpoint pen and a mechanical pencil, there has been known a writing tool having a clip on a back-end of a tool body thereof. As this type of writing tool having a clip, a writing tool in which the clip is composed of a single piece of metal elastic wire rod is disclosed in, e.g., the below-mentioned Patent Document 1. In this writing tool, a single piece of metal elastic wire rod is subjected to bending, such that right and left wire rod portions extend from a bottom base portion to form a U shape, and then opposite ends thereof are attached, respectively, to a pair of mounting holes formed in a lateral portion of a tool body of the writing tool.

CITATION LIST

Patent Document

Patent Document 1: JP2009-039940A

SUMMARY OF INVENTION

Technical Problem

However, in the invention described in the Patent Document 1, when opening the clip from the tool body, a user has to move a writing tip-side section of the clip such that it is spaced apart from the tool body, while holding the tool body. Thus, the operation for opening the clip requires holding the tool body with one hand, and raise the writing tip-side section of the clip with the other hand, i.e., needs to manipulate the writing tool with both hands, which is very burdensome.

The present invention has been made in view of the above problem, and an object thereof is to provide a writing tool comprising a clip composed of a wire rod, wherein the writing tool is capable of allowing a user to open the clip without manipulation with both hands.

Solution to Technical Problem

The present invention provides a writing tool comprising a tool body extending in a longitudinal direction, and a clip member composed of a wire rod and held by a lateral portion of the tool body, wherein a longitudinal intermediate section of the clip member is held by the lateral portion of the tool body, and the clip member is biased toward the tool body so as to cause a writing tip-side section of the clip member to come into contact with the tool body, and wherein the writing tool is configured such that, when a back-end section of the clip member is pushed toward the tool body, a longitudinal writing tip-side section of the clip member is swung to be spaced apart from the tool body.

In the writing tool of the present invention having the above feature, the back-end section of the clip member can be pushed down in a state in which the tool body is gripped by the index finger, middle finger, ring finger, little finger of

2

one hand, so as to cause a fore-end section of the clip member to be spaced apart from the tool body, and thus, the clip member can be opened with respect to the tool body by one-handed manipulation.

5 Preferably, in the writing tool of the present invention, the clip member is formed by bending the wire rod, wherein opposite ends of the wire rod are attached, respectively, to a pair of mounting parts formed in the lateral portion of the tool body, and the clip member is bent into a shape allowing 10 the longitudinal writing tip-side section of the clip member to be biased toward the tool body by elasticity of the wire rod composing the clip member.

According to this feature, the writing tip-side section of 15 the clip member is biased toward the tool body by elasticity of the wire rod composing the clip member, so that the clip member can be composed by a simple configuration, without using any biasing member such as a spring.

More preferably, in the above writing tool, each of the pair 20 of mounting parts is formed of a hole extending in a transverse direction, or a cutout, wherein at least one of the ends of the wire rod is formed with a bent part, and the mounting part corresponding to the at least one end has a relief part expanded as compared with a base end part thereof, wherein the bent part is located in the relief part.

25 According to this feature, at least one of the ends of the wire rod is formed with a bent part, wherein the bent part is located in the relief part, so that it is possible to prevent the at least one end of the wire rod from dropping off from the mounting part.

30 Preferably, in the writing tool of the present invention, the wire rod is bent such that the clip member is at least partly formed to define a certain figure.

According to this feature, an aesthetic property can be given to the clip member.

35 More preferably, in the above writing tool, the tool body comprises a hollow cylindrical-shaped shaft tube and an inner tube disposed inside the shaft tube, and one of the pair of mounting holes is composed of a through-hole, wherein one of the ends of the clip member is disposed inside and 40 held by the through-hole, wherein the through-hole is formed in a boundary surface between the shaft tube and the inner tube.

45 According to this feature, the clip member is held by the through-hole, so that it is possible to prevent easy drop-out of the clip member, and the through-hole is disposed in the boundary surface between the shaft tube and the inner tube, so that the clip member can be easily disposed in the through-hole.

50 Effect of Invention

The present invention makes it possible to provide a writing tool comprising a clip member composed of a wire rod, wherein the writing tool is capable of allowing a user to 55 raise the clip without manipulation with both hands.

BRIEF DESCRIPTION OF DRAWINGS

FIG. 1 is a perspective view showing a writing tool according to a first embodiment of the present invention.

FIG. 2 is a front view showing the writing tool according to the first embodiment.

FIG. 3 is a side view showing the writing tool according to the first embodiment.

65 FIG. 4 is a sectional view showing a shaft tube of the writing tool illustrated in FIG. 1, taken along an axial direction.

FIG. 5A is a perspective view showing an inner tube of the writing tool illustrated in FIG. 1.

FIG. 5B is a front view showing the inner tube of the writing tool illustrated in FIG. 1.

FIG. 5C is a right side view showing the inner tube of the writing tool illustrated in FIG. 1.

FIG. 5D is a left side view showing the inner tube of the writing tool illustrated in FIG. 1.

FIG. 5E is a sectional view taken along the line E-E of FIG. 5B.

FIG. 5F is a sectional view taken along the line F-F of FIG. 5C.

FIG. 6A is a perspective view showing a clip member of the writing tool illustrated in FIG. 1.

FIG. 6B is a front view showing the clip member of the writing tool illustrated in FIG. 1.

FIG. 6C is a side view showing the clip member of the writing tool illustrated in FIG. 1.

FIG. 7 is a side view showing a state in which the clip of the writing tool according to the first embodiment is opened.

FIG. 8 is a perspective view showing a writing tool according to a second embodiment of the present invention.

FIG. 9 is a front view showing the writing tool according to the second embodiment.

FIG. 10 is a side view showing the writing tool according to the second embodiment.

FIG. 11 is a sectional view showing a shaft tube of the writing tool illustrated in FIG. 8, taken along an axial direction.

FIG. 12A is a perspective view showing an inner tube of the writing tool illustrated in FIG. 8.

FIG. 12B is a front view showing the inner tube of the writing tool illustrated in FIG. 8.

FIG. 12C is a right side view showing the inner tube of the writing tool illustrated in FIG. 8.

FIG. 12D is a left side view showing the inner tube of the writing tool illustrated in FIG. 8.

FIG. 12E is a sectional view taken along the line E-E of FIG. 12C.

FIG. 12F is a sectional view taken along the line F-F of FIG. 12B.

FIG. 12G is a sectional view taken along the line G-G of FIG. 12C.

FIG. 13A is a perspective view showing a clip member of the writing tool illustrated in FIG. 8.

FIG. 13B is a front view showing the clip member of the writing tool illustrated in FIG. 8.

FIG. 13C is a side view showing the clip member of the writing tool illustrated in FIG. 8.

FIG. 14A is a front view for explaining a method to attach the clip member of the writing tool according to the second embodiment (part 1).

FIG. 14B is a side view for explaining the method to attach the clip member of the writing tool according to the second embodiment (part 1).

FIG. 15A is a front view for explaining the method to attach the clip member of the writing tool according to the second embodiment (part 2).

FIG. 15B is a side view for explaining the method to attach the clip member of the writing tool according to the second embodiment (part 2).

FIG. 16 is a front view for explaining the method to attach the clip member of the writing tool according to the second embodiment (part 3).

FIG. 17 is a side view showing a state in which the clip of the writing tool according to the second embodiment is opened.

FIG. 18 is a perspective view showing a writing tool according to a third embodiment of the present invention.

FIG. 19A is a perspective view showing a clip member of the writing tool illustrated in FIG. 18.

FIG. 19B is a front view showing the clip member of the writing tool illustrated in FIG. 18.

FIG. 19C is a side view showing the clip member of the writing tool illustrated in FIG. 18.

FIG. 20A is a perspective view showing an inner tube of a writing tool according to a fourth embodiment of the present invention.

FIG. 20B is a front view showing the inner tube of the writing tool according to the fourth embodiment.

FIG. 20C is a right side view showing the inner tube of the writing tool according to the fourth embodiment.

FIG. 20D is a left side view showing the inner tube of the writing tool according to the fourth embodiment.

FIG. 20E is a sectional view taken along the line E-E of FIG. 20C.

FIG. 20F is a sectional view taken along the line F-F of FIG. 20B.

FIG. 20G is a sectional view taken along the line G-G of FIG. 20C.

FIG. 21 is a perspective view showing a writing tool according to a fifth embodiment of the present invention.

FIG. 22 is a front view showing the writing tool according to the fifth embodiment.

FIG. 23 is a side view showing the writing tool according to the fifth embodiment.

FIG. 24 is a sectional view showing a shaft tube of the writing tool illustrated in FIG. 21, taken along an axial direction.

FIG. 25A is a perspective view showing a backward shaft tube of the writing tool according to the fifth embodiment.

FIG. 25B is a front view showing the backward shaft tube of the writing tool according to the fifth embodiment.

FIG. 25C is a side view showing the backward shaft tube of the writing tool according to the fifth embodiment.

FIG. 25D is a sectional view showing the backward shaft tube of the writing tool according to the fifth embodiment, taken along the line D-D of FIG. 25C.

FIG. 25E is a sectional view showing the backward shaft tube of the writing tool according to the fifth embodiment, taken along the line E-E of FIG. 25B.

FIG. 25F is a view showing the backward shaft tube of the writing tool according to the fifth embodiment, as viewed backwardly from the forward side of the backward shaft tube.

FIG. 25G is a view showing the backward shaft tube of the writing tool according to the fifth embodiment, as viewed forwardly from the backward side of the backward shaft tube.

FIG. 26A is a perspective view showing an inner tube of the writing tool illustrated in FIG. 21.

FIG. 26B is a front view showing the inner tube of the writing tool illustrated in FIG. 21.

FIG. 26C is a right side view showing the inner tube of the writing tool illustrated in FIG. 21.

FIG. 26D is a left side view showing the inner tube of the writing tool illustrated in FIG. 21.

FIG. 26E is a sectional view showing the inner tube of the writing tool illustrated in FIG. 21, taken along the line E-E of FIG. 26B.

FIG. 26F is a sectional view showing the inner tube of the writing tool illustrated in FIG. 21, taken along the line F-F of FIG. 26C.

FIG. 26G is a sectional view showing the inner tube of the writing tool illustrated in FIG. 21, taken along the line G-G of FIG. 26C.

FIG. 26H is a sectional view showing the inner tube of the writing tool illustrated in FIG. 21, taken along the line H-H of FIG. 26C.

FIG. 27A is a perspective view showing a clip member of the writing tool illustrated in FIG. 21.

FIG. 27B is a front view showing the clip member of the writing tool illustrated in FIG. 21.

FIG. 27C is a side view showing the clip member of the writing tool illustrated in FIG. 21.

FIG. 28A is a perspective view for explaining a method to attach the clip member to the inner tube and then attach the inner tube to the backward shaft tube, in the writing tool according to the fifth embodiment (part 1).

FIG. 28B is a side view corresponding to FIG. 28A.

FIG. 29A is a perspective view for explaining the method to attach the clip member to the inner tube and then attach the inner tube to the backward shaft tube, in the writing tool according to the fifth embodiment (part 2).

FIG. 29B is a side view corresponding to FIG. 29A.

FIG. 30A is a perspective view for explaining the method to attach the clip member to the inner tube and then attach the inner tube to the backward shaft tube, in the writing tool according to the fifth embodiment (part 3).

FIG. 30B is a side view corresponding to FIG. 30A.

FIG. 31A is a perspective view for explaining the method to attach the clip member to the inner tube and then attach the inner tube to the backward shaft tube, in the writing tool according to the fifth embodiment (part 4).

FIG. 31B is a side view corresponding to FIG. 31A.

FIG. 32A is a sectional view corresponding to FIG. 24, showing the writing tool according to the fifth embodiment in a state after attaching, to the backward shaft tube, the inner tube to which the clip member is attached, and then attaching a knock member and a rotor thereto.

FIG. 32B is a sectional view taken along the line B-B of FIG. 32A.

FIG. 32C is an enlarged sectional view of a region C in FIG. 32B.

FIG. 32D is a sectional view taken along the line D-D of FIG. 32A.

DESCRIPTION OF EMBODIMENTS

First Embodiment

With reference to the drawings, a writing tool according to a first embodiment of the present invention will now be described in detail. It should be noted that, in the aforementioned various embodiments, one side on which a writing tip of a refill is selectively extended and retracted will be referred to as "writing tip-side", "fore-end side" or "forward side", and the other side on which a knock member of a knock mechanism extends will be referred to as "back end-side" or "backward side". Further, an axial direction of a writing tool will be referred to as "longitudinal direction" or "axial direction".

FIGS. 1 to 3 illustrate the writing tool according to the first embodiment, wherein FIG. 1, FIG. 2 and FIG. 3 are, respectively, a perspective view, a front view and a side view. Further, FIG. 4 is a sectional view showing a shaft tube of the writing tool illustrated in FIG. 1, taken along the axial direction. The writing tool 1 according to the first embodiment is a so-called "knock-type ballpoint pen", and configured to be switchable between a state in which a writing tip

portion 4a of a refill element 4 protrudes from a fore-end of a shaft tube 2, and a state in which the writing tip portion 4a of the refill element 4 is housed in the shaft tube 2, through an operation of pushing down a knock member 16 at a back-end of the writing tool, as mentioned later.

As shown in FIGS. 1 to 4, the writing tool 1 according to the first embodiment comprises a tool body 7, and a clip member 8 held by a lateral portion of the tool body 7. The tool body 7 comprises a hollow cylindrical-shaped long shaft tube 2, a refill element 4 housed in the shaft tube 2, and a knock mechanism 6 provided in a back-end of the shaft tube 2. The knock mechanism 6 comprises an inner tube 10, a rotor 12, a spring member 14, and a knock member 16.

The shaft tube 2 is formed in a hollow cylindrical shape whose fore-end is tapered. The shaft tube 2 has a fore-end opening 2a and a back-end opening 2b formed in the fore-end and the back-end thereof, respectively. The shaft tube 2 also has an annular-shaped convex part 2c formed on an inner peripheral surface of the back-end thereof to protrude radially inwardly and extend over the entire inner circumference thereof. Further, the shaft tube 2 has a cutout 2d formed in a back-end edge thereof to have a shape equivalent to that of the after-mentioned clip mounting portion 10c of the inner tube 10.

FIGS. 5A to 5E illustrate the inner tube of the writing tool illustrated in FIG. 1, wherein FIG. 5A, FIG. 5B, FIG. 5C and FIG. 5D are, respectively, a perspective view, a front view, a right side view and a left side view, and FIG. 5E and FIG. 5F are, respectively, a sectional view taken along the line E-E of FIG. 5B and a sectional view taken along the line F-F of FIG. 5C. As shown in FIGS. 5A to 5F, the inner tube 10 comprises a hollow cylindrical-shaped tube body 10a, a back-end portion 10b connected to a back-end of the tube body 10a, and a clip mounting portion 10c connected to the back-end side of the tube body 10a. The tube body 10a, the back-end portion 10b and the clip mounting portion 10c are integrally formed.

The tube body 10a has an approximately hollow cylindrical shape, wherein the outer diameter of the tube body 10a is slightly less than the inner diameter of the shaft tube 2. The tube body 10a has a protrusion 10d formed on an outer peripheral surface of a lower portion thereof to protrude radially outwardly and extend over the entire outer circumference thereof. The tube body 10a also has a cam portion 10f formed on an inner peripheral surface of the back-end thereof. The cam portion 10f is configured to, when the knock member 16 is manually knocked, rotate the rotor 12 in cooperation with the after-mentioned cam portion 12b of the rotor 12 so as to switch between a state in which the writing tip portion 4a of the refill element 4 protrudes from the fore-end opening 2a of the shaft tube 2, and a state in which the writing tip portion 4a of the refill element 4 is housed in the shaft tube 2. As a configuration of the cam portion 10f of the inner tube 10 and the cam portion 12b of the rotor 12, any of well-known configurations may be employed. In the first embodiment, the cam portion 10f of the inner tube 10 has a plurality of convex parts extending forwardly and a plurality of concave parts formed between adjacent ones of the convex parts to extend backwardly.

The back-end portion 10b is formed in a hollow cylindrical shape, wherein the outer diameter thereof is approximately equal to the outer diameter of the shaft tube 2. The back-end portion 10b has a circular through-hole formed to penetrate therethrough in a forward-backward direction.

The clip mounting portion 10c is provided with a given distance from the back-end of the tube body 10a, and formed in a columnar shape extending laterally outwardly. The clip

mounting portion 10c is formed such that side surfaces thereof opposed in a transverse direction (rightward-leftward direction in FIG. 5B) are parallel to each other.

As shown in FIGS. 5C, 5E and 5F, the clip mounting portion 10c has a first mounting hole 10g formed to extend in the transverse direction and opened in a back-end region of the right side surface thereof. The first mounting hole 10g is terminated in a transverse intermediate region of the clip mounting portion 10c, i.e., does not penetrate therethrough to reach the left side surface.

As shown in FIGS. 5D and 5E, the clip mounting portion 10c also has a second mounting hole 10h formed to extend in the transverse direction and opened in a fore-end region of the left side surface thereof. The second mounting hole 10h is terminated in the transverse intermediate region of the clip mounting portion 10c, i.e., does not penetrate therethrough to reach the right side surface. The first mounting hole 10g and the second mounting hole 10h are aligned in the longitudinal direction (i.e., they are located at an equal distance from a central axis of the inner tube 10), wherein the first mounting hole 10g is formed backward of the second mounting hole 10h.

The rotor 12 comprises a backward-side base end portion 12a, and a forward-side cam portion 12b. The base end portion 12a is formed in a hollow cylindrical shape, wherein the outer diameter thereof is less than the outer diameter of the knock member 16. The cam portion 12b is formed in a hollow cylindrical shape, wherein the outer diameter thereof is slightly less than the inner diameter of the tube body 10a of the inner tube 10. The cam portion 12b has a plurality of convex parts formed on an outer surface thereof to extend backwardly and a plurality of concave parts formed between adjacent ones of the convex parts to extend forwardly.

The knock member 16 is formed in a hollow cylindrical shape which is closed on the upper side and opened on the lower side. The outer diameter of the knock member 16 is approximately equal to the inner diameter of the through-hole of the back-end portion 10b of the inner tube 10. The knock member 16 has a protrusion 16a formed on a lower end region of an outer peripheral surface thereof to protrude radially outwardly over the entire outer circumference thereof.

The spring member 14 is installed such that a back-end thereof is in contact with a fore-end of the refill element 4, and a fore-end thereof is in contact with the fore-end of the shaft tube 2. Thus, the spring member 14 operates to bias the refill element 4 backwardly.

In an assembled state, the inner tube 10 is disposed such that the tube body 10a is inserted from the back-end opening 2b of the shaft tube 2 and located inside the shaft tube 2, and the back-end portion 10b is in contact with a back-end edge of the shaft tube 2. Further, the protrusion 10d of the inner tube 10 is located on the fore-end side with respect to the convex part 2c of the shaft tube 2, and thereby the inner tube 10 is fixed to the shaft tube 2. The knock member 16 is inserted through the through-hole of the back-end portion 10b of the inner tube 10 from the forward side, and the protrusion 16a of the knock member 16 is located inside the tube body 10a of the inner tube 10. The base end portion 12a of the rotor 12 is inserted inside the knock member 16 from the forward side, and a fore-end edge of the knock member 16 is in contact with a back-end surface of the cam portion 12b of the rotor 12. Further, a fore-end surface of the cam portion 12b of the rotor 12 is in contact with the refill element 4. Thus, the rotor 12 and the knock member 16 are biased backwardly through the refill element 4.

When the knock member 16 is pushed down in the above state, the rotor 12 is rotated to switch between a state in which the convex parts of the cam portion 12b of the rotor 12 are meshed with the concave parts of the cam portion 10f of the inner tube 10, and a state in which tops of the convex parts of the cam portion 10f of the inner tube 10 are in contact with respective tops of the convex parts of the cam portion 12b of the rotor 12, and thereby switch between a state in which the writing tip portion 4a of the refill element 4 is housed in the shaft tube 2, and a state in which the writing tip portion 4a of the refill element 4 protrudes from the fore-end of the shaft tube 2.

FIGS. 6A to 6C illustrate the clip member of the writing tool illustrated in FIG. 1, wherein FIG. 6A, FIG. 6B and FIG. 6C are, respectively, a perspective view, a front view and a side view. It should be noted here that FIG. 6C shows the clip member in a state in which it is detached from the inner tube. As shown in FIGS. 6A to 6C, the clip member 8 is formed by subjecting a single piece of metal wire rod made of stainless steel or the like to bending. The clip member 8 has: a fore-end section 8A formed in a U shape; a back-end section 8C formed in an approximately rectangular shape; and an intermediate section 8B between the fore-end section 8A and the back-end section 8C.

The fore-end section 8A is composed of a forward part of a first longitudinal portion 8b, a forward part of a second longitudinal portion 8c, and an arc-shaped portion 8a connecting a fore-end of the first longitudinal portion 8b and a fore-end of the second longitudinal portion 8c. The first longitudinal portion 8b extends backwardly from a right (right side in FIG. 6B) end of the arc-shaped portion 8a. The second longitudinal portion 8c extends backwardly from a left (left side in FIG. 6B) end of the arc-shaped portion 8a. The first longitudinal portion 8b extends to a position backward of the after-mentioned second end 8i of the intermediate section 8B. The second longitudinal portion 8c extends to the back-end section 8C beyond the intermediate section 8B.

The back-end section 8C is composed of: a back-end of the second longitudinal portion 8c; a first transverse portion 8d extending rightwardly (in a rightward direction in FIG. 6B) from the back-end of the second longitudinal portion 8c; a third longitudinal portion 8e extending forwardly from a right (right side in FIG. 6B) end of the first transverse portion 8d; and a second transverse portion 8f extending leftwardly (in a leftward direction in FIG. 6B) from the fore-end of the third longitudinal portion 8e. The second transverse portion 8f is located backward of the after-mentioned first end 8h. Further, a fourth longitudinal portion 8g extends forwardly from a left (left in FIG. 6B) end of the second transverse portion 8f.

The intermediate section 8B has a first end 8h extending leftwardly (in the leftward direction in FIG. 6B) from a back-end of the first transverse portion 8d, and a second end 8i extending rightwardly (in the rightward direction in FIG. 6B) from a fore-end of the fourth longitudinal portion 8g. The first end 8h is located backward of the second end 8i.

In a state in which the clip member 8 is detached from the inner tube 10, the first longitudinal portion 8b is tilted such that it extends obliquely backwardly toward a radially central side (in a rightward direction in FIG. 6C), with respect to a direction along which the second longitudinal portion 8c extends. Further, the third longitudinal portion 8e and the fourth longitudinal portion 8g are tilted such that they extend obliquely backwardly toward a radially outward side (in a leftward direction in FIG. 6C), with respect to the direction along which the second longitudinal portion 8c

extends. Thus, the first end **8h** is located closer to the tool body than the second end **8i**. It should be noted here that a biasing force of the clip member **8** can be obtained as long as at least the first longitudinal portion **8b** is tilted.

In the assembled state, the first mounting hole **10g** and the second mounting hole **10h** of the clip mounting portion **10c** of the inner tube **10** are arranged such that they are aligned in the longitudinal direction with a given distance from an outer peripheral surface of the shaft tube **2**. The first end **8h** and the second end **8i** are inserted, respectively, into the first mounting hole **10g** and the second mounting hole **10h** in the clip mounting portion **10c** of the inner tube **10**, so as to fix the clip member **8**. That is, the clip member **8** is attached in a state in which it is deformed such that the first longitudinal portion **8b**, the third longitudinal portion **8e** and the fourth longitudinal portion **8g** become approximately parallel to the second longitudinal portion **8c**.

Based on the above configuration, the intermediate section **8B** of the clip member **8** is held by the clip mounting portion **10c**. Further, since the clip member **8** is attached in the deformed state as mentioned above, the fore-end section **8A** is biased toward the tool body **7** by an elastic force of the metal wire rod composing the clip member **8**. Therefore, in a state in which the clip member **8** is attached to the inner tube **10**, the fore-end section **8A** of the clip member **8** is in contact with the outer peripheral surface of the shaft tube **2** of the tool body **7**, as shown in FIG. 3.

FIG. 7 is a side view showing a state in which the clip of the writing tool according to the first embodiment is opened. When the back-end section **8C** of the clip member **8** is pushed radially inwardly toward the tool body **7**, the fore-end section **8A** of the clip member **8** is swung about a fulcrum consisting of the intermediate section **8B** held by the clip mounting portion **10c**, i.e., moved radially outwardly to be spaced apart from the tool body **7**, as shown in FIG. 7. Therefore, a user of the writing tool **1** according to the first embodiment can push down the back-end section **8C** of the clip member **8** in a state in which he/she grips the shaft tube **2** of the tool body **7** by the index finger, middle finger, ring finger, little finger of one hand, thereby causing the fore-end section **8A** of the clip member **8** to be spaced apart from the tool body **7** to open the clip member **8** with respect to the tool body **7**.

In the present invention, the expression "swinging the clip with respect to the tool body" includes not only swinging the clip strictly about a single pivot, but also, through an operation of manually pushing the back-end section of the clip member radially inwardly in the state in which the intermediate section of the clip member is supported, moving the fore-end section of the clip member radially outwardly, as in the first embodiment.

The first embodiment can bring out the following advantageous effects.

In the first embodiment, the intermediate section **8B** of the clip member **8** is held by the lateral portion of the tool body **7**, and, when the back-end section **8C** of the clip member **8** is pushed toward the tool body **7**, the fore-end section **8A** of the clip member **8** is swung to be spaced apart from the tool body **7**. Thus, the back-end section **8C** of the clip member **8** can be pushed down in a state in which the shaft tube **2** of the tool body **7** is gripped by the index finger, middle finger, ring finger, little finger of one hand, thereby opening the clip member **8** by one-handed manipulation.

In the first embodiment, the fore-end section **8A** is biased toward the tool body **7** by elasticity of the wire rod composing the clip member **8**, so that the clip member **8** can be

composed by a simple configuration, without using any biasing member such as a spring.

Here, in the first embodiment, the clip mounting portion **10c** is provided in the inner tube **10**, and the clip member **8** is attached to the clip mounting portion **10c**. Alternatively, such a clip mounting portion may be provided on a lateral surface of the shaft tube **2**, and the clip member **8** may be attached thereto.

Further, in the first embodiment, the first mounting hole **10g** and the second mounting hole **10h** are aligned in the longitudinal direction, and, in the state in which the clip member **8** is detached from the inner tube **10**, the first end **8h** is located closer to the tool body than the second end **8i**. However, the present invention is not limited thereto. For example, even in a case where the clip member **8** is formed in a flat shape, the writing tip-side second mounting hole **10h** may be formed closer to the tool body **7** than the first mounting hole **10g**. In this case, the fore-end section of the clip member **8** can also be biased toward the tool body **7**.

Further, in the first embodiment, the first mounting hole **10g** and the second mounting hole **10h** are provided to fix the first end **8h** and the second end **8i** of the clip member **8** thereto. Alternatively, a cutout may be formed.

Further, although the first embodiment has been described based on an example where the present invention is applied to a knock-type ballpoint pen, a writing tool to which the present invention is applicable is not limited thereto. For example, the present invention is also applicable to a knock-type mechanical pencil, and a writing tool equipped with no knock mechanism. Further, the present invention may be applied in a case where a cap is attached to a cap of a cap-type writing tool.

Second Embodiment

Next, with reference to the drawings, a writing tool according to a second embodiment of the present invention will be described in detail. In the following description, a similar element or component to that in the first embodiment will be assigned with the same reference sign, and detailed description thereof will be omitted.

FIGS. 8 to 11 illustrate the writing tool according to the second embodiment, wherein FIG. 8, FIG. 9 and FIG. 10 are, respectively, a perspective view, a front view and a side view. Further, FIG. 11 is a sectional view showing a shaft tube of the writing tool illustrated in FIG. 8, taken along the axial direction. The writing tool according to the second embodiment is a so-called "knock-type ballpoint pen", and configured to be switchable between a state in which a writing tip portion **4a** of a refill element **4** protrudes from a fore-end of a shaft tube **2**, and a state in which the writing tip portion **4a** of the refill element **4** is housed in the shaft tube **2**, through an operation of manually pushing down a knock member **16** at a back-end of the writing tool, as mentioned later. The writing tool **101** according to the second embodiment is different from the first embodiment in terms of only the configurations of the after-mentioned inner tube **110** and the after-mentioned clip member **108**, and the remaining configurations are similar to those in the first embodiment.

As shown in FIGS. 8 to 11, the writing tool **102** according to the second embodiment comprises a tool body **107**, and a clip member **108** held by a lateral portion of the tool body **107**. The tool body **107** comprises a hollow cylindrical-shaped shaft tube **2**, a refill element **4** housed in the shaft tube **2**, and a knock mechanism **106** provided in a back-end

11

of the shaft tube 2. The knock mechanism 106 comprises an inner tube 110, a rotor 12, a spring member 14, and a knock member 16.

FIGS. 12A to 12G illustrate the inner tube of the writing tool illustrated in FIG. 8, wherein FIG. 12A, FIG. 12B, FIG. 12C and FIG. 12D are, respectively, a perspective view, a front view, a right side view and a left side view. Further, FIG. 12E, FIG. 12F and FIG. 12G are, respectively, a sectional view taken along the line E-E of FIG. 12C, a sectional view taken along the line F-F of FIG. 12B and a sectional view taken along the line G-G of FIG. 12C. As shown in FIGS. 12A to 12G, the inner tube 110 comprises a hollow cylindrical-shaped tube body 110a, a back-end portion 110b connected to a back-end of the tube body 110a, and a clip mounting portion 110c connected to the back-end side of the tube body 110a. The tube body 110a, the back-end portion 110b and the clip mounting portion 110c are integrally formed.

The tube body 110a has an approximately hollow cylindrical shape, wherein the outer diameter of the tube body 110a is slightly less than the inner diameter of the shaft tube 2. The tube body 110a also has a cam portion 110f formed on an inner peripheral surface of the back-end thereof. The cam portion 110f is configured to, when the knock member 16 is manually pushed, rotate the rotor 12 in cooperation with the after-mentioned cam portion 12b of the rotor 12 so as to switch between a state in which a writing tip portion 4a of the refill element 4 protrudes from a fore-end opening 2a of the shaft tube 2, and a state in which the writing tip portion 4a of the refill element 4 is housed in the shaft tube 2. As a configuration of the cam portion 110f of the inner tube 110 and the cam portion 12b of the rotor 12, any of well-known configurations may be employed.

The back-end portion 110b is formed in a hollow cylindrical shape, wherein the outer diameter thereof is approximately equal to the outer diameter of the shaft tube 2. The back-end portion 110b has a circular through-hole formed to penetrate therethrough in a forward-backward direction.

The clip mounting portion 110c is provided with a given distance from the back-end of the tube body 110a, and formed in a columnar shape extending laterally outwardly. The clip mounting portion 110c is formed such that side surfaces thereof opposed in a transverse direction (rightward-leftward direction in FIG. 12B) are parallel to each other.

The clip mounting portion 110c has a first mounting cutout 110g formed in a back-end thereof. The first mounting cutout 110g is composed of a cutout extending from a radially outward edge of the back-end of the clip mounting portion 110c (left edge of an upper end of the clip mounting portion 110c in FIG. 12C) obliquely forwardly (obliquely downwardly in FIG. 12C) and radially inwardly (in a rightward direction in FIG. 12C). A columnar-shaped receiving part 110g1 is formed at a termination of the first mounting cutout 110g.

The clip mounting portion 110c also has a second mounting hole 110h formed in a fore-end thereof to penetrate therethrough in the transverse direction. The second mounting hole 110h has a right-side base end part 110h1 and a left-side relief part 110h2. The base end part 110h1 is opened on the right side surface of the clip mounting portion 110c, and formed in a columnar shape. The relief part 110h2 is opened on the left side surface of the clip mounting portion 110c, and formed in a columnar shape having a diameter greater than that of the base end part 110h1.

The receiving part 110g1 of the first mounting cutout 110g and the second mounting hole 110h are aligned in the

12

longitudinal direction (i.e., they are located at an equal distance from a central axis of the inner tube 110), wherein the first mounting cutout 110g is formed backward of the second mounting hole 110h.

5 The configurations of the rotor 12, the knock member 16 and the spring member 14 are similar to those of the first embodiment.

In an assembled state, the inner tube 110 is disposed such that the tube body 110a is inserted from a back-end opening 2b of the shaft tube 2 and located inside the shaft tube 2, and the back-end portion 110b is in contact with a back-end edge of the shaft tube 2. The knock member 16 is inserted through the through-hole of the back-end portion 110b of the inner tube 110 from the forward side, and a protrusion 16a of the knock member 16 is located inside the tube body 110a of the inner tube 110. A base end portion 12a of the rotor 12 is inserted inside the knock member 16 from the forward side, and a fore-end edge of the knock member 16 is in contact with a back-end surface of the cam portion 12b of the rotor 12. Further, a fore-end surface of the cam portion 12b of the rotor 12 is in contact with the refill element 4. Thus, the rotor 12 and the knock member 16 are biased backwardly through the refill element 4.

20 When the knock member 16 is pushed down in the above state, the rotor 12 is rotated to switch between a state in which convex parts of the cam portion 12b of the rotor 12 are meshed with concave parts of the cam portion 110f of the inner tube 110, and a state in which tops of convex parts of the cam portion 110f of the inner tube 110 are in contact with respective tops of the convex parts of the cam portion 12b of the rotor 12, and thereby switch between a state in which the writing tip portion 4a of the refill element 4 is housed in the shaft tube 2, and a state in which the writing tip portion 4a of the refill element 4 protrudes from a fore-end of the shaft tube 2.

25 FIGS. 13A to 13C illustrate the clip member of the writing tool illustrated in FIG. 8, wherein FIG. 13A, FIG. 13B and FIG. 13C are, respectively, a perspective view, a front view and a side view. It should be noted here that FIG. 13A to 13C show the clip member in a state in which it is detached from the inner tube. As shown in FIGS. 13A to 13C, the clip member 108 is formed by subjecting a single piece of metal wire rod made of stainless steel or the like to bending. The 30 clip member 108 has: a fore-end section 108A formed in a U shape; a back-end section 108C formed in a U shape; and an intermediate section 108B between the fore-end section 108A and the back-end section 108C.

35 The fore-end section 108A is composed of a forward part of a first longitudinal portion 108b, a forward part of a second longitudinal portion 108c, and a first arc-shaped portion 108a connecting a fore-end of the first longitudinal portion 108b and a fore-end of the second longitudinal portion 108c. The first longitudinal portion 108b extends 40 backwardly from a right (right side in FIG. 13B) end of the first arc-shaped portion 108a to the intermediate section 108B. The second longitudinal portion 108c extends backwardly from a left (left side in FIG. 13B) end of the first arc-shaped portion 108a to the back-end section 108C beyond the intermediate section 108B.

45 The back-end section 108C is composed of: a back-end of the second longitudinal portion 108c; a second arc-shaped portion 108d extending accurately and rightwardly (in a rightward direction in FIG. 13B) from the back-end of the second longitudinal portion 108c; and a third longitudinal portion 108e extending forwardly from a right (right side in FIG. 13B) end of the second arc-shaped portion 108d.

13

The intermediate section 108B has a first end 108f extending leftwardly (in a leftward direction in FIG. 13B) from a fore-end of the third longitudinal portion 108e, and a second end 108g extending leftwardly (in the leftward direction in FIG. 13B) from a back-end of the first longitudinal portion 108b. The second end 108g has a bent part 108h formed in a distal area thereof to extend obliquely forwardly and leftwardly.

In a state in which the clip member 108 is detached from the inner tube 110, the first longitudinal portion 108b is tilted such that it extends obliquely backwardly and radially outwardly (in a leftward direction in FIG. 13C), with respect to a direction along which the second longitudinal portion 108c extends. Thus, the first end 108f is located closer to the tool body than the second end 108g.

In the assembled state, the receiving part 110g1 of the first mounting cutout 110g and the second mounting hole 110h of the clip mounting portion 110c of the inner tube 110 are arranged such that they are aligned in the longitudinal direction with a given distance from an outer peripheral surface of the shaft tube 2. The first end 108f and the second end 108g are inserted, respectively, into the first mounting cutout 110g and the second mounting hole 110h in the clip mounting portion 110c of the inner tube 110, so as to fix the clip member 108. At this time, the bent part 108h in the distal area of the second end 108g is located within the relief part 110h2 of the second mounting hole 110h. Thus, the clip member 108 is attached in a state in which it is deformed such that the first longitudinal portion 108b becomes approximately parallel to the second longitudinal portion 108c.

In this way, the intermediate section 108B of the clip member 108 is held by the clip mounting portion 110c. Further, since the clip member 108 is attached in the deformed state as mentioned above, the fore-end section 108A is biased toward the tool body 7 by an elastic force of the metal wire rod composing the clip member 108. Therefore, in a state in which the clip member 108 is attached to the inner tube 110, the fore-end section 108A of the clip member 108 is in contact with the outer peripheral surface of the shaft tube 2 of the tool body 107, as shown in FIG. 10.

In an operation of attaching the clip member 108, as shown in FIGS. 14A and 14B, in a state in which fore-and back-ends and obverse and reverse sides of the clip member 108 are inverted (i.e., the second end 108g is located backward of the first end 108f and closer to the tool body 107 than the first end 108f), the bent part 108h of the second end 108g is first inserted into the base end part 110h1 of the second mounting hole 110h, and then the second end 108g is further inserted into the second mounting hole 110h such that the bent part 108h is located within the relief part 110h2, by rotating the clip member 108 about the second end 108g such that the first arc-shaped portion 108a is positioned at the back end-side.

Subsequently, as shown in FIGS. 15A and 15B, the first arc-shaped portion 108a is curved such that a part of the second longitudinal portion 108c on the side of the second arc-shaped portion 108d is located on the left side of the tool body 107. Then, as indicated by the arrowed line in FIG. 15B, the clip member 108 is rotated about the second end 108g such that the first arc-shaped portion 108a is located at a forwardmost position.

Subsequently, as shown in FIG. 16, the third longitudinal portion 108e and the first end 108f are inserted into the first mounting cutout 110g from a lateral side thereof to allow the first end 108f to be disposed in the receiving part 110g1. In this way, the clip member 108 can be attached to the clip

14

mounting portion 110c. Here, the clip member 108 in an attached state in which the first end 108f is disposed in the receiving part 110g1 can not be detached unless the clip member 108 or the inner tube 110 is destroyed.

FIG. 17 is a side view showing a state in which the clip of the writing tool according to the second embodiment is opened. When the back-end section 108C of the clip member 108 is pushed radially inwardly toward the tool body 107, the fore-end section 108A of the clip member 108 is 10 swung about a fulcrum consisting of the intermediate section 108B held by the clip mounting portion 110c, i.e., moved radially outwardly to be spaced apart from the tool body 107, as shown in FIG. 17. Therefore, a user of the writing tool 101 according to the second embodiment can push 15 down the back-end section 108C of the clip member 108 in a state in which he/she grips the shaft tube 2 of the tool body 107 by the index finger, middle finger, ring finger, little finger of one hand, thereby causing the fore-end section 108A of the clip member 108 to be spaced apart from the 20 tool body 107 to open the clip member 108 with respect to the tool body 107.

The second embodiment can bring out the following advantageous effects.

In the second embodiment, the intermediate section 108B 25 of the clip member 108 is held by the lateral portion of the tool body 107, and, when the back-end section 108C of the clip member 108 is pushed toward the tool body 107, the fore-end section 108A of the clip member 108 is swung to be spaced apart from the tool body 107. Thus, the back-end section 108C of the clip member 108 can be pushed down 30 in a state in which the shaft tube 2 of the tool body 107 is gripped by the index finger, middle finger, ring finger, little finger of one hand, thereby opening the clip member 108 by one-handed manipulation.

In the second embodiment, the fore-end section 108A is 35 biased toward the tool body 107 by elasticity of the wire rod composing the clip member 108, so that the clip member 108 can be composed by a simple configuration, without using any biasing member such as a spring.

In the second embodiment, the second mounting hole 110h is composed of a transversely-extending hole, and formed with the relief part 110h2, and the bent part 108h of the second end 108g is disposed in the relief part 110h2. Thus, the bent part 108h formed in the second end 108g of 40 the clip member 108 can prevent the clip member 108 from dropping off from the second mounting hole 110h.

Here, in the second embodiment, the first mounting cutout 110g is formed of a cutout, and the second mounting hole 110h is formed of a transversely-extending hole. Alternatively, the cutout may be changed to a transversely-extending hole, or the transversely-extending hole may be changed to a cutout. Further, in the second embodiment, the bent part 108h is formed in the second end 108g of the clip member 108. Alternatively, such a bent part may be provided in the 45 first end 108f.

Further, in the second embodiment, the clip mounting portion 110c is provided in the inner tube 110, and the clip member 108 is attached to the clip mounting portion 110c. Alternatively, such a clip mounting portion may be provided 50 on a lateral surface of the shaft tube 2, and the clip member 108 may be attached thereto.

Further, in the second embodiment, the first mounting cutout 110g and the second mounting hole 110h are aligned in the longitudinal direction, and, in the state in which the clip member 108 is detached from the inner tube 110, the first end 108f is located closer to the tool body than the second end 108g. However, the present invention is not 55

limited thereto. For example, even in a case where the clip member 208 is formed in a flat shape, the writing tip-side second mounting hole 110h may be formed closer to the tool body 107 than the first mounting cutout 110g. In this case, the fore-end section of the clip member 208 can also be biased toward the tool body 107.

Further, although the second embodiment has been described based on an example where the present invention is applied to a knock-type ballpoint pen, a writing tool to which the present invention is applicable is not limited thereto. For example, the present invention is also applicable to a knock-type mechanical pencil, and a writing tool equipped with no knock mechanism. Further, the present invention may be applied in a case where a clip is attached to a cap of a cap-type writing tool.

Third Embodiment

Next, with reference to the drawings, a writing tool according to a third embodiment of the present invention will be described in detail. In the following description, a similar element or component to that in the second embodiment will be assigned with the same reference sign, and detailed description thereof will be omitted.

FIG. 18 is a perspective view showing the writing tool according to the third embodiment. As shown in FIG. 18, the writing tool 202 according to the third embodiment comprises a tool body 107, and a clip member 208 held by a lateral portion of the tool body 107. The writing tool 201 according to the third embodiment is different from the second embodiment in terms of only the configuration of the clip member 208, and the remaining configurations are similar to those in the second embodiment.

FIGS. 19A to 19C illustrate the clip member of the writing tool illustrated in FIG. 18, wherein FIG. 19A, FIG. 19B and FIG. 19C are, respectively, a perspective view, a front view and a side view. It should be noted here that FIG. 19C shows the clip member in a state in which it is detached from an inner tube 110.

As shown in FIGS. 19A to 19C, the clip member 208 is formed by subjecting a single piece of metal wire rod made of stainless steel or the like to bending. The clip member 208 has: a fore-end section 208A formed in a U shape; a back-end section 208C formed in a figure shape; and an intermediate section 208B between the fore-end section 208A and the back-end section 208C.

The fore-end section 208A is composed of a forward part of a first longitudinal portion 208b, a forward part of a second longitudinal portion 208c, and a first arc-shaped portion 208a connecting a fore-end of the first longitudinal portion 208b and a fore-end of the second longitudinal portion 208c. The first longitudinal portion 208b extends backwardly from a right (right side in FIG. 19B) end of the first arc-shaped portion 208a to the intermediate section 208B. The second longitudinal portion 208c extends backwardly from a left (left side in FIG. 19B) end of the first arc-shaped portion 208a to the back-end section 208C beyond the intermediate section 208B.

The back-end section 208C is composed of: a back-end of the second longitudinal portion 208c; a figure portion 208d formed in a figure shape imitating a character such as an animal; and a third longitudinal portion 208e extending forwardly from a right (right side in FIG. 19B) end of the second arc-shaped portion 208d. The shape of the figure portion 208d is not limited to a character such as an animal, but may be any other shape imitating a letter or a pattern.

The intermediate section 208B has a first end 208f extending leftwardly (in a leftward direction in FIG. 19B) from a fore-end of the third longitudinal portion 208e, and a second end 208g extending leftwardly (in the leftward direction in FIG. 19B) from a back-end of the first longitudinal portion 208b.

In a state in which the clip member 208 is detached from the inner tube 110, the first longitudinal portion 208b is tilted such that it extends obliquely backwardly and radially outwardly (in a leftward direction in FIG. 19C), with respect to a direction along which the second longitudinal portion 208c extends. Thus, the first end 208f is located closer to the tool body than the second end 208g.

In an assembled state, the first end 208f and the second end 208g are inserted, respectively, into a first mounting cutout 110g and a second mounting hole 110h in a clip mounting portion 110c of the inner tube 110, so as to fix the clip member 208. Thus, the clip member 208 is attached in a state in which it is deformed such that the first longitudinal portion 208b becomes approximately parallel to the second longitudinal portion 208c.

In this way, the intermediate section 208B of the clip member 208 is held by the clip mounting portion 110c. Further, since the clip member 208 is attached in the deformed state as mentioned above, the fore-end section 208A is biased toward the tool body 107 by an elastic force of the metal wire rod composing the clip member 208.

Therefore, in a state in which the clip member 208 is attached to the inner tube 110, the fore-end section 208A of the clip member 208 is in contact with an outer peripheral surface of a shaft tube 2 of the tool body 107, as shown in FIG. 18.

In the third embodiment, when the back-end section 208C of the clip member 208 is pushed radially inwardly toward the tool body 107, the fore-end section 208A of the clip member 208 is swung about a fulcrum consisting of the intermediate section 208B held by the clip mounting portion 110c, i.e., moved radially outwardly to be spaced apart from the tool body 107. Therefore, a user of the writing tool 201 according to the third embodiment can push down the back-end section 208C of the clip member 208 in a state in which he/she grips the shaft tube 2 of the tool body 107 by the index finger, middle finger, ring finger, little finger of one hand, thereby causing the fore-end section 208A of the clip member 208 to be spaced apart from the tool body 107 to open the clip member 208 with respect to the tool body 107.

In addition to the effects of the second embodiment, the third embodiment can bring out the following advantageous effect.

In the third embodiment, since the figure portion 208d obtained by bending the wire rod is formed in the back-end section 208C of the clip member 208, an aesthetic property can be given to the clip member 208.

It should be noted that a structure for attaching the clip member 208 to the tool body 107 is not limited to that in the third embodiment, but may employ a similar structure as that in the first or second embodiment. In the third embodiment, a figure shape is formed in the back-end section 208C. Alternatively, it may be formed in the fore-end section 208A or the like.

Further, in the third embodiment, the clip mounting portion 110c is provided in the inner tube 110, and the clip member 208 is attached to the clip mounting portion 110c. Alternatively, such a clip mounting portion may be provided on a lateral surface of the shaft tube 2, and the clip member 208 may be attached thereto.

Next, with reference to the drawings, a writing tool according to a fourth embodiment of the present invention will be described in detail.

FIGS. 20A to 20G illustrate an inner tube of the writing tool according to the fourth embodiment, wherein FIG. 20A, FIG. 20B, FIG. 20C and FIG. 20D are, respectively, a perspective view, a front view, a right side view and a left side view. Further, FIG. 20E, FIG. 20F and FIG. 20G are, respectively, a sectional view taken along the line E-E of FIG. 20C, a sectional view taken along the line F-F of FIG. 20B and a sectional view taken along the line G-G of FIG. 20C. The writing tool according to the fourth embodiment is different from the second embodiment in terms of only the configuration of the after-mentioned inner tube, and the remaining configurations are similar to those in the second embodiment. Specifically, the writing tool according to the fourth embodiment comprises a tool body, and a clip member 108 held by a lateral portion of the tool body. The clip member attached to the inner tube in the fourth embodiment is the same as that in the second embodiment. The tool body comprises a shaft tube 2, a refill element 4 housed in the shaft tube 2, and a knock mechanism provided in a back-end of the shaft tube 2, wherein the knock mechanism comprises an inner tube 310, a rotor 12, a spring member 14, and a knock member 16. The inner tube 310 is attached to the back-end of the shaft tube 2.

As shown in FIGS. 20A to 20G, the inner tube 310 comprises a hollow cylindrical-shaped tube body 310a, a back-end portion 310b connected to a back-end of the tube body 310a, and a clip mounting portion 310c connected to the back-end side of the tube body 310a. The tube body 310a, the back-end portion 310b and the clip mounting portion 310c are integrally formed.

The tube body 310a has an approximately hollow cylindrical shape, wherein the outer diameter of the tube body 310a is slightly less than the inner diameter of the shaft tube 2. The tube body 310a also has a cam portion 310f formed on an inner peripheral surface of the back-end thereof. The cam portion 310f is configured to, when the knock member 16 is manually pushed, rotate the rotor 12 in cooperation with the after-mentioned cam portion 12b of the rotor 12 so as to switch between a state in which a writing tip portion 4a of the refill element 4 protrudes from a fore-end opening 2a of the shaft tube 2, and a state in which the writing tip portion 4a of the refill element 4 is housed in the shaft tube 2. As a configuration of the cam portion 310f of the inner tube 310 and the cam portion 12b of the rotor 12, any of well-known configurations may be employed.

The back-end portion 310b is formed in a hollow cylindrical shape, wherein the outer diameter thereof is approximately equal to the outer diameter of the shaft tube 2. The back-end portion 310b has a circular through-hole formed to penetrate therethrough in a forward-backward direction.

The clip mounting portion 310c is provided with a given distance from the back-end of the tube body 310a, and formed in a columnar shape extending laterally outwardly. The clip mounting portion 310c is formed such that side surfaces thereof opposed in a transverse direction (rightward-leftward direction in FIG. 20B) are parallel to each other.

The clip mounting portion 310c has a first mounting cutout 310g formed in a back-end thereof. The first mounting cutout 310g is composed of a cutout extending from a radially inward edge of the back-end of the clip mounting portion 310c (right edge of an upper end of the clip mount-

ing portion 310c in FIG. 20C) forwardly (downwardly in FIG. 20C), and then bending to extend obliquely forwardly (obliquely downwardly in FIG. 20C) and radially outwardly (in a leftward direction in FIG. 20C). A columnar-shaped receiving part 310g1 is formed at a termination of the first mounting cutout 310g.

The clip mounting portion 310c also has a second mounting hole 310h formed in a fore-end thereof to penetrate therethrough in the transverse direction. The second mounting hole 310h has a right-side base end part 310h1 and a left-side relief part 310h2. The base end part 310h1 is opened on the right side surface of the clip mounting portion 310c, and formed in a columnar shape. The relief part 310h2 is opened on the left side surface of the clip mounting portion 310c, and formed in a columnar shape having a diameter greater than that of the base end part 310h1.

The receiving part 310g1 of the first mounting cutout 310g and the second mounting hole 310h are aligned in the longitudinal direction (i.e., they are located at an equal distance from a central axis of the inner tube 310), wherein the first mounting cutout 310g is formed backward of the second mounting hole 310h.

In the fourth embodiment, a first end 108f and a second end 108g of the clip member 108 are inserted, respectively, into the first mounting cutout 310g and the second mounting hole 310h in the clip mounting portion 310c of the inner tube 310, so as to fix the clip member 108 to the inner tube 310. At this time, a bent part 108h in a distal area of the second end 108g is located within the relief part 310h2 of the second mounting hole 310h. An attaching method for the clip member 108 is similar to that in the second embodiment.

In the fourth embodiment, in a state in which the clip member 108 is attached, an outer surface of the clip mounting portion 310c of the inner tube 310 to which the clip member 108 is attached is located radially outwardly so as to prevent exposure of the ends of the first mounting cutout 310g, thereby providing an improved an aesthetic property.

Although the fourth embodiment has been described based on an example where the present invention is applied to a knock-type ballpoint pen, a writing tool to which the present invention is applicable is not limited thereto. For example, the present invention is also applicable to a knock-type mechanical pencil, and a writing tool equipped with no knock mechanism. Further, the present invention may be applied in a case where a cap is attached to a cap of a cap-type writing tool.

In the present invention, the expression “swinging the clip with respect to the tool body” includes not only swinging the clip strictly about a single pivot, but also, through an operation of manually pushing the back-end section of the clip member radially inwardly in the state in which the intermediate section of the clip member is supported, moving the fore-end section of the clip member radially outwardly, as in the above embodiments.

With reference to the drawings, a writing tool according to a fifth embodiment of the present invention will now be described in detail.

FIGS. 21 to 23 illustrate the writing tool according to the fifth embodiment, wherein FIG. 21, FIG. 22 and FIG. 23 are, respectively, a perspective view, a front view and a side view. Further, FIG. 24 is a sectional view showing a shaft tube of the writing tool illustrated in FIG. 21, taken along the axial direction. The writing tool 401 according to the fifth embodiment is a so-called “Kern knock-type ballpoint pen”,

and configured to be switchable between a state in which a writing tip portion **404a** of a refill element **404** protrudes from a fore-end of a shaft tube **402**, and a state in which the writing tip portion **404a** of the refill element **404** is housed in the shaft tube **402**, through an operation of manually pushing down a knock member **416** at a back-end of the writing tool, as mentioned later.

As shown in FIGS. 21 to 24, the writing tool **401** according to the fifth embodiment comprises a tool body **407**, and a clip member **408** held by a lateral portion of the tool body **407**. The clip member **408** is held by the after-mentioned clip holding unit **418** formed on a backward side of the tool body **407**. The tool body **407** comprises a hollow cylindrical-shaped long shaft tube **402**, a refill element **404** housed in the shaft tube **402**, and a knock mechanism **406** provided in a back-end of the shaft tube **402**. The knock mechanism **406** comprises an inner tube **410**, a rotor **412**, a spring member **414**, and a knock member **416**.

The shaft tube **402** is formed in a hollow cylindrical shape whose fore-end is tapered. The shaft tube **402** is formed by connecting a forward shaft tube **402A** on the side of the fore-end and a backward shaft tube **402B** on the side of the back-end together. FIGS. 25A to 25E illustrate the backward shaft tube of the writing tool according to the fifth embodiment, wherein: FIG. 25A, FIG. 25B and FIG. 25C are, respectively, a perspective view, a front view and a side view; FIG. 25D and FIG. 25E are, respectively, a sectional view taken along the line D-D of FIG. 25C and a sectional view taken along the line E-E of FIG. 25B; and FIG. 25F and FIG. 25G are, respectively, a view as viewed backwardly from the forward side and a view as viewed forwardly from the backward side. As shown in FIG. 24, a spiral thread **402A1** is formed on an outer peripheral surface of a back-end of the forward shaft tube **402A**. Further, as shown in FIGS. 25A to 25G, a spiral thread **402B1** is formed on an inner peripheral surface of the backward shaft tube **402B**. The back-end of the forward shaft tube **402A** is inserted into the backward shaft tube **402B** from the side of a fore-end of the backward shaft tube **402B**, and the spiral thread **402A1** of the forward shaft tube **402A** is threadingly engaged with the spiral thread **402B1** of the backward shaft tube **402B**, so that the forward shaft tube **402A** and the backward shaft tube **402B** are coupled together to form the shaft tube **402**. The forward shaft tube **402A** has a fore-end opening **402a** formed in a fore-end thereof. Further, the backward shaft tube **402B** has a back-end opening **402b** formed in the back-end thereof.

The backward shaft tube **402B** has a pair of radially-narrowing portions **402c** formed on an inner peripheral surface of the back-end thereof to protrude radially inwardly. Each of the radially-narrowing portions **402c** is formed in a rectangular shape as view from the radially inward side, wherein a back-end of the radially-narrowing portion **402c** is formed to have an inclined surface. The pair of radially-narrowing portions **402c** are arranged at positions opposed to each other across a central axis of the shaft tube **402**.

Further, the backward shaft tube **402B** has a cutout **402d** formed in a back-end edge thereof to have a shape equivalent to that of the after-mentioned extension part **410b1** of the inner tube **410**.

A fore-end of the cutout **402d** is formed with a first clip holding portion **402e**. The first clip holding portion **402e** comprises a base part **402e1** standingly provided on an outer peripheral surface the backward shaft tube **402B**, and an engagement part **402e2** connected to the base part **402e1**. The base part **402e1** is formed to have a flat radially-outer surface. The base part **402e1** is also formed to have a

backward surface extending obliquely forwardly and radially outwardly. Further, the base part **402e1** has a recess **402e3** which is formed on the radially-outer surface thereof to extend from one of transversely-opposed edges to a widthwise (transverse) intermediate position. The engagement part **402e2** is standingly provided on a fore-end region of the radially-outer surface of the base part **402e1**. The engagement part **402e2** is formed to have a flat radially-outer surface, and a back-end surface extending obliquely forwardly and radially inwardly.

FIGS. 26A to 26H illustrate the inner tube of the writing tool illustrated in FIG. 21, wherein FIG. 26A, FIG. 26B, FIG. 26C and FIG. 26D are, respectively, a perspective view, a front view, a right side view and a left side view, and FIG. 26E, FIG. 26F, FIG. 26G and FIG. 26H are, respectively, a sectional view taken along the line E-E of FIG. 26B, a sectional view taken along the line F-F of FIG. 26C, a sectional view taken along the line G-G of FIG. 26C and a sectional view taken along the line H-H of FIG. 26C. As shown in FIGS. 26A to 26H, the inner tube **410** comprises a hollow cylindrical-shaped tube body **410a**, a back-end portion **410b** connected to a back-end of the tube body **410a**, and a second clip holding portion **410c** connected to the back-end side of the tube body **410a**. The tube body **410a**, the back-end portion **410b** and the second clip holding portion **410c** are integrally formed.

The tube body **410a** has an approximately hollow cylindrical shape, wherein the outer diameter of the tube body **410a** is slightly less than the inner diameter of the shaft tube **402**. The tube body **410a** has recesses **410d** formed on a forward-side portion thereof to become concave radially inwardly, wherein a peripheral edge of each of the recesses **410d** is formed as a step. Each of the recesses **410d** is internally provided with a base portion **410e1** formed to extend along a forward edge of the recess **410d**, and an elastically deformable portion **410e2** extending backwardly from the base portion **410e1**. The base portion **410e1** is formed such that an inner peripheral surface thereof has the same cylindrical surface shape as that of an inner peripheral surface of the tube body **410a**, and an outer peripheral surface thereof has a cylindrical surface shape with a smaller diameter than that of the tube body **410a**. The elastically deformable portion **410e2** has the same cylindrical surface shape as that of the base portion **410e1**, and is formed in a cantilever configuration extending backwardly. The base portion **410e1** has a protrusion **410e3** formed on a fore-end thereof to protrude radially outwardly. A backward edge and circumferentially-opposed edges of the base portion **410e1** are surrounded by a through-hold **410e4**.

The tube body **410a** also has a cam portion **410f** (FIG. 26E) formed on the inner peripheral surface of the back-end thereof. The cam portion **410f** is configured to, when the knock member **416** is manually knocked, rotate the rotor **412** in cooperation with the after-mentioned cam portion **412b** of the rotor **412** so as to switch between a state in which a writing tip portion **404a** of the refill element **404** protrudes from the fore-end opening **402a** of the shaft tube **402**, and a state in which the writing tip portion **404a** of the refill element **404** is housed in the shaft tube **402**. As a configuration of the cam portion **410f** of the inner tube **410** and the cam portion **412b** of the rotor **412**, any of well-known configurations may be employed. In the fifth embodiment, the cam portion **410f** of the inner tube **410** has a plurality of convex parts extending forwardly and a plurality of concave parts formed between adjacent ones of the convex parts to extend backwardly.

The back-end portion **410b** is formed in a hollow cylindrical shape, wherein the outer diameter thereof is approximately equal to the outer diameter of the shaft tube **402**. The back-end portion **410b** has a circular through-hole formed to penetrate therethrough in a forward-backward direction. The back-end portion **410b** also has an extension part **410b1** formed to extend forwardly along the outer peripheral surface of the tube body **410a**.

The second clip holding portion **410c** is provided continuously with a fore-end of the extension part **410b1**, and formed in a columnar shape extending laterally outwardly. The second clip holding portion **410c** is formed such that side surfaces thereof opposed in a transverse direction (rightward-leftward direction in FIG. 26B) are parallel to each other.

The second clip holding portion **410c** has a rising part **410c1** rising radially outwardly from the tube body **410a**, and an extension part **410c2** provided continuously with a radially-outer end of the rising part **410c1**. The rising part **410c1** has a forward surface extending obliquely forwardly and radially outwardly. A portion of the extension part **410c2** located forward of the rising part **410c1** is formed with a protrusion **410c3**. Thus, a first recess **410g** is formed at a corner between the rising part **410c1** and the protrusion **410c3** and on the forward side of the connection between the rising part **410c1** and the extension part **410c2**. Further, a second recess **410h** is formed at a corner on the backward side of the connection between the rising part **410c1** and the extension part **410c2**. The protrusion **410c3** has a forward surface extending obliquely backwardly and radially outwardly.

The first recess **410g** is opened radially inwardly and extends penetratively in a transverse direction (rightward-leftward direction in FIG. 26B). The first recess **410g** is formed to have a semicircular cross-section in a radially-outer region (bottom region), and a rectangular cross-section in a radially-inner region thereof, and to have a U-shaped cross-section in its entirety. The first recess **410g** is formed such that one (left region in FIG. 26F) of two transversely divided regions is diametrically expanded as compared with the other region (right region in FIG. 26F) to form a relief part. The second recess **410h** is opened backwardly and extends penetratively in the transverse direction.

The rotor **412** comprises a backward-side base end portion **412a**, and a forward-side cam portion **412b**. The base end portion **412a** is formed in a hollow cylindrical shape, wherein the outer diameter thereof is less than the outer diameter of the knock member **416**. The cam portion **412b** is formed in a hollow cylindrical shape, wherein the outer diameter thereof is slightly less than the inner diameter of the tube body **410a** of the inner tube **410**. The cam portion **412b** has a plurality of convex parts formed on an outer surface thereof to extend backwardly and a plurality of concave parts formed between adjacent ones of the convex parts to extend forwardly.

The knock member **416** is formed in a hollow cylindrical shape which is closed on the upper side and opened on the lower side. The outer diameter of the knock member **416** is approximately equal to the inner diameter of the through-hole of the back-end portion **410b** of the inner tube **410**. The knock member **416** has a protrusion **416a** formed on a lower end region of an outer peripheral surface thereof to protrude radially outwardly over the entire outer circumference thereof.

The spring member **414** is installed such that a back-end thereof is in contact with a fore-end of the refill element **404**, and a fore-end thereof is in contact with the fore-end of the

shaft tube **402**. Thus, the spring member **414** operates to bias the refill element **404** backwardly.

In an assembled state, the inner tube **410** is disposed such that the tube body **410a** is inserted from the back-end opening **402b** of the shaft tube **402** and located inside the shaft tube **402**, and the back-end portion **410b** is in contact with a back-end edge of the shaft tube **402**. The knock member **416** is inserted through the through-hole of the back-end portion **410b** of the inner tube **410** from the forward side, and the protrusion **416a** of the knock member **416** is located inside the tube body **410a** of the inner tube **410**. The base end portion **412a** of the rotor **412** is inserted inside the knock member **416** from the forward side, and a fore-end edge of the knock member **416** is in contact with a back-end surface of the cam portion **412b** of the rotor **412**. Further, a fore-end surface of the cam portion **412b** of the rotor **412** is in contact with the refill element **404**. Thus, the rotor **412** and the knock member **416** are biased backwardly through the refill element **404**.

When the knock member **416** is pushed down in the above state, the rotor **412** is rotated to switch between a state in which the convex parts of the cam portion **412b** of the rotor **412** are meshed with the concave parts of the cam portion **410f** of the inner tube **410**, and a state in which tops of the convex parts of the cam portion **410f** of the inner tube **410** are in contact with respective tops of the convex parts of the cam portion **412b** of the rotor **412**, and thereby switch between a state in which the writing tip portion **404a** of the refill element **404** is housed in the shaft tube **402**, and a state in which the writing tip portion **404a** of the refill element **404** protrudes from the fore-end of the shaft tube **402**.

FIGS. 27A to 27C illustrate the clip member of the writing tool illustrated in FIG. 21, wherein FIG. 27A, FIG. 25B and FIG. 27C are, respectively, a perspective view, a front view and a side view. It should be noted here that FIG. 27A to 27C show the clip member in a state in which it is detached from the inner tube. As shown in FIGS. 27A to 27C, the clip member **408** is formed by subjecting a single piece of metal wire rod made of stainless steel or the like to bending. The clip member **408** has: a fore-end section **408A** formed in a U shape; a back-end section **408C** formed in a U shape; and an intermediate section **408B** between the fore-end section **408A** and the back-end section **408C**.

The fore-end section **408A** is composed of a forward part of a first longitudinal portion **408b**, a forward part of a second longitudinal portion **408c**, and a first arc-shaped portion **408a** connecting a fore-end of the first longitudinal portion **408b** and a fore-end of the second longitudinal portion **408c**. The first longitudinal portion **408b** extends backwardly from a right (right side in FIG. 27B) end of the first arc-shaped portion **408a** to the intermediate section **408B**. The second longitudinal portion **408c** extends backwardly from a left (left side in FIG. 27B) end of the first arc-shaped portion **408a** to the back-end section **408C** beyond the intermediate section **408B**.

The back-end section **408C** is composed of: a back-end of the second longitudinal portion **408c**; a second arc-shaped portion **408d** extending accurately and rightwardly (in a rightward direction in FIG. 27B) from the back-end of the second longitudinal portion **408c**; and a third longitudinal portion **408e** extending forwardly from a right (right side in FIG. 27B) end of the second arc-shaped portion **408d**.

The intermediate section **408B** has a first end **408f** extending leftwardly (in a leftward direction in FIG. 27B) from a fore-end of the third longitudinal portion **408e**, and a second end **408g** extending leftwardly (in the leftward direction in FIG. 27B) from a back-end of the first longitudinal portion

408b. The second end 408g has a bent part 408h formed in a distal area thereof to extend obliquely forwardly and leftwardly.

In a state in which the clip member 408 is detached from the inner tube 410, the first longitudinal portion 408b is tilted such that it extends obliquely backwardly and radially outwardly (in a leftward direction in FIG. 27C), with respect to a direction along which the second longitudinal portion 408c extends. Thus, the first end 408f is located closer to the tool body than the second end 408g.

In an operation of assembling the writing tool according to the fifth embodiment, the clip member is first attached to the inner tube. FIGS. 28A, 29A, 30A and 31A are perspective views for explaining a method to attach the clip member to the inner tube and then attach the inner tube to the backward shaft tube, in the writing tool according to the fifth embodiment. Further, FIGS. 28B, 29B, 30B and 31B are side views corresponding to FIGS. 28A, 29A, 30A and 31A, respectively.

In order to attach the clip member 408 to the inner tube 410, first of all, the clip member 408 is moved forwardly as indicated by the arrowed line in FIG. 28B to insert the first end 408f into the second recess 410h from the backward side, as shown in FIGS. 28A and 28B.

Subsequently, as shown in FIGS. 29A and 29B, the second end 408g of the clip member 408 is pushed radially inwardly toward the inner tube 410. Then, the second end 408g is fitted into the first recess 410g from the radially inner side. In this process, the second end is fitted such that the bent part 408h thereof is positioned in the diametrically expanded region of the first recess 410g.

Subsequently, as shown in FIGS. 30A and 30B, the inner tube 410 is moved forwardly as indicated by the arrowed line in FIGS. 30A and 30B to allow the extension part 410b1 of the inner tube 410 to be fitted into the cutout 402d of the backward shaft tube 402B, and inserted into the back-end opening 402b of the backward shaft tube 402B. In this way, the extension part 410b1 of the inner tube 410 is positioned such that it is fitted in the cutout 402d of the backward shaft tube 402B. Thus, the recesses 410d of the inner tube 410 are aligned with the radially-narrowing portions 402c of the backward shaft tube 402B in the axial direction.

In this process, as shown in FIGS. 31A and 31B, when the back-end section 408C of the clip member 408 is pushed radially inwardly toward the backward shaft tube 402B, the fore-end section 408A of the clip member 408 is swung about a fulcrum consisting of the intermediate section 408B held by the second clip holding portion 410c, so that the fore-end section 408A of the clip member 408 is moved radially outwardly to be spaced apart from the backward shaft tube 402B. Then, when the inner tube 410 is inserted forwardly in this state, a fore-end edge of the inner tube 410 can climb over the radially-narrowing portions 402c because the back-end of each of the radially-narrowing portions 402c is formed to have an inclined surface. The inner tube 410 is inserted until the inclined forward surface of the rising part 410c1 in the second clip holding portion 410c of the inner tube 410 is brought into contact with the inclined backward surface of the base part 402e1 of the backward shaft tube 402B. In this way, each of the radially-narrowing portions 402c of the backward shaft tube 402B is fitted into a corresponding one of the recesses 410d of the inner tube 410. Thus, even when a pullout force oriented backwardly with respect to the backward shaft tube 402B to move acts on the inner tube 410, a fore-end edges of each of the radially-narrowing portions 402c of the backward shaft tube 402B is brought into contact with the step of a forward

region of the peripheral edge of a corresponding one of the recesses 410d of the inner tube 410, thereby preventing the inner tube 410 from being separated from the backward shaft tube 402B. Further, a radially-inner surface of the radially-narrowing portion 402c of the backward shaft tube 402B is brought into contact with the protrusion 410e3 formed on the elastically deformable portion 410e2, and thereby the elastically deformable portion 410e2 is bent radially inwardly. As a result, an inner edge of a back-end of 10 the elastically deformable portion 410e2 protrudes radially inwardly beyond the outer periphery of the cam portion 412b of the rotor 412.

Further, when the forward inclined surface of the rising part 410c1 of the inner tube 410 comes into contact with the 15 backward inclined surface of the base part 402e1 of the backward shaft tube 402B, the first clip holding portion 402e of the backward shaft tube 402B and the second clip holding portion 410c of the inner tube 410 are combined together to form a clip holding unit 418 provided to laterally extend 20 from the tool body 407. In addition, the first recess 410g of the inner tube 410 and the recess 402e3 of the backward shaft tube 402B are integrated to form a through-hole 420. This through-hole 420 is formed such that one of the 25 opposite ends thereof has a larger diameter than the other end. The second end 408g is disposed in the through-hole 420, and the bent part 408h is disposed in the large-diameter relief part in the through-hole 420. In this way, the second end 408g of the clip member 408 is held in the through-hole 420. As above, the clip member 408 is fixed by attaching the 30 first end 408f to the second recess 410h of the inner tube 410 and attaching the second end 408g to the through-hole 420. That is, the second recess 410h of the inner tube 410 and the through-hole 420 composing the clip holding unit 418 function as a mounting portion. The through-hole 420 35 (mounting portion) is formed in a boundary surface between the second clip holding portion 410c of the inner tube 410 and the first clip holding portion 402e of the backward shaft tube 402B.

After the inner tube 410 is attached to the backward shaft 40 tube 402B, the knock member 416 is inserted into the backward shaft tube 402B from the forward side of the backward shaft tube 402B, and then the rotor 412 is inserted 45 into the backward shaft tube 402B from the forward side of the backward shaft tube 402B. FIGS. 32A to 32D illustrate 50 in the writing tool according to the fifth embodiment in a state after attaching, to the backward shaft tube, the inner tube to which the clip member is attached, and then attaching the knock member and the rotor thereto, wherein FIG. 32A is a sectional view corresponding to FIG. 24, and FIG. 55 32B, FIG. 32C and FIG. 32D are, respectively, a sectional view taken along the line B-B of FIG. 32A, an enlarged 60 sectional view of a region C in FIG. 32B, and a sectional view taken along the line D-D of FIG. 32A. As shown in FIGS. 32A to 32D, the elastically deformable portions 410e2 extend 65 backwardly from the base portions 410e1. Thus, during an operation of inserting the rotor 412, even if the elastically deformable portions 410e2 protrude radially inwardly, the rotor 412 can be smoothly inserted. Then, after the rotor 412 is inserted backwardly beyond the elastically 70 deformable portions 410e2, the rear-end edges of the elastically deformable portions 410e2 protrude radially inwardly beyond the outer periphery of the rotor 412 again. Thus, even if an operator attempts to move the rotor 412 forwardly, an outer peripheral edge of the fore-end of the cam portion 412b of the rotor 412 will be brought into contact with the 75 back-end edges of the elastically deformable portions 410e2. Therefore, even when the writing tool is disassembled

during replacement of the refill element 4, the rotor 412 is held inside the backward shaft tube 402B by the elastically deformable portions 410e2.

Subsequently, the spring member is disposed in the fore-end of the forward shaft tube 402A, and the forward shaft tube 402A and the backward shaft tube 402B are threadingly connected together in a state in which the refill element 404 is disposed such that the fore-end thereof is inserted into the inside of the spring member 414. Thus, the refill element 404 is biased backwardly by the spring member 414 and brought into the fore-end of the rotor 412. Then, the knock member 416 is biased backwardly through the rotor 412, and the protrusion 416a of the knock member 416 is brought into contact with a fore-end edge of the back-end portion 410b of the inner tube 410. In this way, the assembling of the writing tool 401 is completed.

In the assembled state, when the back-end section 408C of the clip member 408 is pushed radially inwardly toward the tool body 407, the fore-end section 408A of the clip member 408 is swung about a fulcrum consisting of the intermediate section 408B held by the second clip holding portion 410c, i.e., moved radially outwardly to be spaced apart from the tool body 407. Therefore, a user of the writing tool 401 according to the fifth embodiment can push down the back-end section 408C of the clip member 408 in a state in which he/she grips the shaft tube 402 of the tool body 407 by the index finger, middle finger, ring finger, little finger of one hand, thereby causing the fore-end section 408A of the clip member 408 to be spaced apart from the tool body 407 to open the clip member 408 with respect to the tool body 407.

In the present invention, the expression "swinging the clip with respect to the tool body" includes not only swinging the clip strictly about a single pivot, but also, through an operation of manually pushing the back-end section of the clip member radially inwardly in the state in which the intermediate section of the clip member is supported, moving the fore-end section of the clip member radially outwardly, as in the above embodiments.

The fifth embodiment can bring out the following advantageous effects.

In the fifth embodiment, the intermediate section 408B of the clip member 408 is held by the lateral portion of the tool body 407, and, when the back-end section 408C of the clip member 408 is pushed toward the tool body 407, the fore-end section 408A of the clip member 408 is swung to be spaced apart from the tool body 407. Thus, the back-end section 408C of the clip member 408 can be pushed down in a state in which the shaft tube 402 of the tool body 407 is gripped by the index finger, middle finger, ring finger, little finger of one hand, thereby opening the clip member 408 by one-handed manipulation.

In the fifth embodiment, the fore-end section 408A is biased toward the tool body 407 by elasticity of the wire rod composing the clip member 408, so that the clip member 408 can be composed by a simple configuration, without using any biasing member such as a spring.

Here, in the fifth embodiment, the through-hole 420 is formed as a hole extending in the transverse direction, wherein a relief part is formed in the through-hole 420, and the bent part of the second end 408g is disposed in the relief part. Thus, the bent part 408h formed in the second end 408g of the clip member 408 makes it possible to prevent the clip member 408 from dropping off from the through-hole 420.

In the fifth embodiment, the clip holding unit 418 has the through-hole 420, and the clip member 408 is composed of a wire rod, wherein a portion of the wire rod is disposed and

held in the through-hole 420, and the through-hole 420 is formed in the boundary surface between the shaft tube 2 and the inner tube 410. According to this feature, the clip member 408 is held by the through-hole 420, so that it is possible to prevent easy drop-out of the clip member 408. Further, the through-hole 420 is formed in the boundary surface between the shaft tube 2 and the inner tube 410, so that it is possible to easily dispose the clip member 408 inside the through-hole 420.

The writing tool according to the fifth embodiment comprises the hollow cylindrical-shaped shaft tube 402, the inner tube 410 disposed inside the shaft tube 402, and the rotor 412 disposed inside the inner tube 410, wherein the inner tube 410 is formed with the elastically deformable portions 410e2 which protrude radially inwardly beyond the outer periphery of the rotor 412, in an assembled state where the inner tube 410 is disposed inside the shaft tube 402 at a position forward of the rotor 412. According to this feature, when the inner tube 410 is disposed inside the shaft tube 402, the elastically deformable portions 410e2 protrude radially inwardly beyond the outer periphery of the rotor 412. Thus, even during replacement of the refill element 404, or the like, the rotor 412 is in contact with the elastically deformable portions 410e2, so that it is possible to prevent the rotor 412 from being separated from the shaft tube 402.

In the fifth embodiment, the shaft tube 402 has the radially-narrowing portions 402c formed on the inner peripheral surface thereof, wherein the outer peripheral surfaces of the elastically deformable portions 410e2 are brought into contact with the radially-narrowing portions 402c, thereby protruding radially inwardly. According to this feature, the elastically deformable portions 410e2 can be deformed to protrude radially inwardly by disposing the inner tube 410 inside the shaft tube 402, so that it is possible to prevent separation of the rotor 412 without causing structural complication of the inner tube 410.

In the fifth embodiment, the inner tube 410 has the steps 40 along the peripheral edges of the recesses 410d in the outer peripheral surface of the inner tube 410, wherein, when a pullout force acts on the inner tube 410, the steps are engaged with the radially-narrowing portions 402c to resist the pullout force. According to this feature, the steps can be engaged with the radially-narrowing portions 402c so as to fix the inner tube 410 to the shaft tube 402.

In the fifth embodiment, each of the elastically deformable portions 410e2 is formed in a cantilever configuration extending backwardly. According to this feature, the elastically deformable portion 410e2 can be configured to, when the inner tube is disposed inside the shaft tube, protrude radially inwardly with a simple configuration.

In the fifth embodiment, the writing tool 401 has the clip member 408 provided along the shaft tube 402, wherein the shaft tube 402 and the inner tube 410 are combined together to form the clip holding unit 418 for holding the clip member 408. According to this feature, the operation of attaching the clip member 408 can be facilitated.

In the fifth embodiment, the clip holding unit 418 has the through-hole 420, and the clip member 408 is composed of a wire rod, wherein a portion of the wire rod is disposed and held in the through-hole 420, and the through-hole 420 is formed in the boundary surface between the shaft tube 2 and the inner tube 410. According to this feature, the clip member 408 is held by the through-hole 420, so that it is possible to prevent easy drop-out of the clip member 408. Further, the through-hole 420 is formed in the boundary

surface between the shaft tube 2 and the inner tube 410, so that it is possible to easily dispose the clip member 408 inside the through-hole 420.

Here, in the fifth embodiment, the through-hole 420 and the second recess 410h are aligned in the longitudinal direction, and, in the state in which the clip member 408 is detached from the inner tube 410, the first end 408h is located closer to the tool body than the second end 408i. However, the present invention is not limited thereto. For example, even in a case where the clip member 408 is formed in a flat shape, the writing tip-side second recess 410h may be formed closer to the tool body 407 than the through-hole 420. In this case, the fore-end section of the clip member 408 can also be biased toward the tool body 407.

Further, in the fifth embodiment, the through-hole 420 and the second recess 410h are provided to fix the first end 408h and the second end 408i of the clip member 408 thereto. Alternatively, a cutout may be formed.

Further, although the fifth embodiment has been described based on an example where the present invention is applied to a knock-type ballpoint pen, a writing tool to which the present invention is applicable is not limited thereto. For example, the present invention is also applicable to a knock-type mechanical pencil, and a writing tool equipped with no knock mechanism.

Further, the present invention may be applied in a case where a cap is attached to a cap of a cap-type writing tool.

The invention claimed is:

1. A writing tool comprising:
 a tool body extending in a longitudinal direction; and
 a clip member composed of a wire rod and held by a 40
 lateral portion of the tool body,

wherein a longitudinal intermediate section of the clip member is held by the lateral portion of the tool body, and the clip member is biased toward the tool body so as to cause a writing tip-side section of the clip member to come into contact with the tool body,
 wherein the writing tool is configured such that, when a back-end section of the clip member is pushed toward the tool body, a longitudinal writing tip-side section of the clip member is swung to be spaced apart from the tool body,
 wherein the clip member is configured to be formed by bending the wire rod, and
 wherein opposite ends of the wire rod are attached, respectively, to a pair of mounting parts formed in the lateral portion of the tool body and separated along the longitudinal direction, and the clip member is bent into a shape allowing the longitudinal writing tip-side section of the clip member to be biased toward the tool body by elasticity of the wire rod composing the clip member.

2. The writing tool as recited in claim 1, wherein each of the pair of mounting parts is formed of a hole extending in a transverse direction, or a cutout, and wherein at least one of the ends of the wire rod is formed with a bent part, and one of the pair of mounting parts corresponding to the at least one end has a relief part expanded as compared with a base end thereof, wherein the bent part is located in the relief part.

3. The writing tool as recited in claim 1, wherein the wire rod is bent such that the clip member is at least partly formed to draw a certain figure.

4. The writing tool as recited in claim 1, wherein the tool body comprises a hollow cylindrical-shaped shaft tube and an inner tube disposed inside the shaft tube, and one of the pair of mounting holes is composed of a through-hole, and wherein one of the ends of the clip member is disposed inside and held by the through-hole, wherein the through-hole is formed in a boundary surface between the shaft tube and the inner tube.
